UNITED STATES PATENT OFFICE.

THOMAS COYLE, OF APPONAUG, RHODE ISLAND.

DESIGN FOR A BENCH-BRACKET.

SPECIFICATION forming part of Design No. 29,980, dated January 10, 1899.

Application filed December 15, 1898. Serial No. 699,386. Term of patent 7 years.

To all whom it may concern:

Be it known that I, THOMAS COYLE, of Apponaug, in the county of Kent and State of Rhode Island, have invented and produced a new and original Design for Bench-Brackets, of which the following is a specification, reference being had to the accompanying drawings, forming part thereof.

Figure 1 is a perspective view of the bench-bracket, showing the design. Fig. 2 is a side view of the same.

The bench-bracket is used by carpenters and others to form a support detachably secured to the side of a carpenter's or other bench.

The leading features of my design consist in the upwardly-extending projection *a* and the hooked lateral extension *b* of a triangular bracket.

In the drawings, *A* indicates a triangular bracket; *A'*, a triangular opening in the bracket; *a*, an upwardly-extending projection; *b*, a laterally-extending hooked projection having the beveled edges *b'* on each side of the lateral projection *b*; *c*, a raised bead extending along the inclined face of the bracket.

Having thus described my invention, what I claim as new, and desire to secure by Letters Patent, is—

The design for a bench-bracket substantially as herein shown and described.

In witness whereof I have hereunto set my hand.

THOMAS COYLE.
